[57] CLAIM

The ornamental design for a bathroom storage cabinet, as shown and described.

DESCRIPTION

FIG. 1 is a perspective view of a bathroom storage cabinet showing my new design;

FIG. 2 is a front view thereof;

FIG. 3 is a rear view thereof;

FIG. 4 is a front view of the door portion thereof;

FIG. 5 is a rear view thereof;

FIG. 6 is a top view of a bathroom storage device; and,

FIG. 7 is a bottom view thereof.

The toilet paper and plunger shown in FIG. 1 are for illustrative purposes only and form no part of the claimed design.
